[57] CLAIM

The ornamental design for a holder for supporting a trac and the rear end of a snowmobile, as shown and described.

DESCRIPTION

FIG. 1 is a side elevation view of a holder for supporting a trac and the rear end of a snowmobile showing my new design, the opposite side being a mirror image of that shown;

FIG. 2 is a top plan view thereof;

FIG. 3 is a bottom plan view thereof;

FIG. 4 is a front elevation view thereof;

FIG. 5 is a rear elevation view thereof; and

FIG. 6 is a perspective view thereof on a reduced scale, it being understood that the broken lines are for illustrative purposes only and form no part of the claimed design.

FIG.2

FIG.5

FIG.1

FIG.4

FIG.3

FIG.6
